COMBINATION LAMP AND LOUD SPEAKER

Filed Feb. 11, 1924

Inventor
Fred C. Caswell

UNITED STATES PATENT OFFICE.

FRED C. CASWELL, OF MINNEAPOLIS, MINNESOTA, ASSIGNOR OF ONE-HALF TO
LAWRENCE F. FAGERSTROM, OF MINNEAPOLIS, MINNESOTA.

COMBINATION LAMP AND LOUD SPEAKER.

Application filed February 11, 1924. Serial No. 691,944.

My invention relates to an improved combination lamp and loud speaker.

Following the recent rapid strides in the development of radio broadcasting and receiving equipment, numerous so-called loud speakers have been produced. These loud speakers largely include upright amplifying horns with the bells thereof directed horizontally or simple conical horns arranged with their axes approximately horizontally so that the sound may be thrown toward a listener or closely grouped listeners. Objections are raised against the conventional loud speakers, one of which is that the same cannot be equally well heard in all parts of a room when the device is placed centrally of the room as on a center table. Another objection is raised against metallic, grating sounds which are commonly amplified to an annoying degree.

One object of my invention is to combine a radio loud speaker in a table, floor, ceiling or wall lamp, the combination of the two articles being so accomplished that certain elements of one article are supplanted by elements of the other, whereby duplication of parts is avoided and a compact, unitary, sightly and efficient combination lamp and loud speaker is produced.

Another object is to supply in an article of the present nature an upright horn and a shade cupping the atmosphere about the open end of the horn, said shade and horn uniting in amplifying the sounds from the reproducer and the latter serving to deflect the sounds in all directions, and temper the same.

A further object is to provide an article of this kind including an adjustable shutter device arranged transversely of the axis of the horn outlet and adapted to variably obstruct the passage of sound waves through the shade, the adjustability of said device serving to attain the best sound producing effect in a given article according to the design and proportion thereof and to the material employed in the shade.

A further object is to provide for an assemblage of parts wherein the post or standard of the shade-supporting lighting fixture, the horn, and the loud speaker unit are all mounted on a common base and in axial alignment, whereby the necessary parts are reduced to a minimum and grouped into

compact, sightly form capable of producing 55 pleasing amplification of sound from said unit.

With the foregoing and other objects in view, which will appear in the following description, the invention resides in the novel 60 combination and arrangement of parts and in the details of construction hereinafter described and claimed.

In the drawings, Fig. 1 is an elevational view of an article embodying my invention, 65 certain parts thereof being broken away to expose interior structural make-up; Fig. 2 is a bottom view of the base; Fig. 3 is an enlarged perspective view of the fixture anchor; Fig. 4 is a fragmentary sectional 70 view illustrating portions of the fixture and shade, also the shutter device for the central opening in the shade and Fig. 5 is a plan view of the parts shown in Fig. 4.

Referring to the drawings, it will be observed that the illustrated form of my improvement includes a base A, a loud speaker unit B, a horn C for said unit, a lighting fixture and shade support D and a shade E. The speaker unit B is carried within a recess 75 in the bottom of the base A and opens upwardly therethrough, covered wires 10 to said unit being led into the base A through a bushing 11 therein. This loud speaker unit B may be of any approved design and 80 is preferably removably held in place within the base A by means of yielding clips 12. The horn C stands in upright position with its reduced end in registration with the mouth of the speaker unit B. Within said 85 end of said horn is an anchor F resembling a tripod in form, the same having legs 13, feet 14 and a head 15. The feet 14 are recessed in the base A and secured thereto by screws 16. The legs 13 reach upwardly and inwardly 90 within the horn C and support the anchor head 15 axially thereof. Each leg 13, near the foot thereof, is formed with an upright portion or riser 13^a. These risers 13^a supply 95 horn centering and securing elements and are provided with threaded bores 13^b to receive screws 17 for attaching the horn C to the anchor F. A decorative annular moulding 18 covers the joint between the horn C and base A and hides the horn securing 100 screws 17 and the feet 14 of the anchor F. The lighting fixture and shade support D is 105 of ordinary design, the same including a

2 tubular stem 19, a hollow head 20, tubular couplings 21 reaching outward from said head, lamp sockets 22 carried by said couplings, a threaded shade centering tip 23 and a nut 24 fitted on said tip. The stem 19 of this fixture D is threaded at its lower end in the head 15 of the anchor F, the corded wire 25 reaching from the sockets 22 through the couplings 21, fixture head 20 and stem 19 being threaded through said anchor head 15 and passed outward from the base A through a bushing 26 therein. Being thus supported, the fixture D is held axially of the horn C and entirely free from contact therewith, the result being that full and unimpaired resonance of tone is produced by said horn.

The shade E is of customary design and includes the usual hub 27 with spokes 28 secured thereto and reaching outward to a central ring 29 forming the crown of the shade. Said shade E also has an ordinary drooping top or cover 30 with a skirt 31 and a covering fringe 32. The hub 27 fits over the threaded tip 23 and the nut 24, turned down on said tip, binds the shade E in place upon the fixture D. The shade E is supported near the bell of the horn in position cupping the atmosphere about the mouth thereof and, in addition to shading light from the lamps, aids the horn C in amplifying the tones issuing from the loud speaker unit B. Said shade E also tends to render mechanical grating sounds less pronounced, as I have found in practice, and together with the horn C produces decidedly more effective and pleasing results in reception than with a horn alone.

To best adapt shades of different designs, proportions and materials to a given horn and speaker unit, I supply a shutter device G consisting merely of two superimposed discs 33, 34 of paper board. These discs have central apertures therein formed to receive the tip 23 and are removably placed on said tip between the head 20 of the fixture D and the binding nut 24. A forked clip 35 reaching upward from the upper disc 34 embraces a spoke 28 of the shade E and a pin 36 reaching downward from the lower disc 33 catches in the head 20 of the fixture D. Both discs 33, 34 are formed with openings 37 arranged to register upon relative rotation of said discs. Thus, it will be understood that by loosening the nut 24 and turning the shade E on the fixture D any degree of opening within the limits of the shutter device G may be obtained and that by again setting said nut 24, the adjustment made may be retained. The deflection of sound waves in greater or less degree by means of this shutter device G provides for the best amplification with given complementary equipment in shades of various designs and materials. The exposed portion

or shank of the horn C appears to be the lamp standard and its graceful contour lends a pleasing appearance to the article without betraying the nature thereof. In simulating the presently popular vase lamps, the lower portion of the horn C may be encompassed with a shell 38 (dotted lines, Fig. 1) of the desired contour, care being taken to avoid contact between said shell and horn.

In designing different forms of articles embodying the present invention, I have found that the construction is well adapted to use not only in table lamps as shown, but in ceiling and floor lamps as well.

In ceiling lamps, the structure is inverted, the base A then constituting a ceiling plate. In floor lamps, the base A usually constitutes an enlargement in the lamp standard near the top thereof. In any of the types mentioned many varied and pleasing effects in outward appearance may be produced, the same efficient results being obtained through the coaction of the various elements as hereinbefore pointed out.

Changes in the specific form of my invention, as herein disclosed, may be made within the scope of what is claimed without departing from the spirit of my invention.

Having described my invention, what I claim as new and desire to protect by Letters Patent is:

1. In an article of the class described, the combination of a base adapted to receive a reproducing unit, an anchor secured to the base axially of the outlet of such unit, a horn for such unit, the reduced end thereof being designed to fit over said anchor, said anchor including horn centering and securing means, a lighting and shade-supporting fixture reaching through the horn without contact therewith and secured to said anchor, and a shade carried by said fixture and cupping the atmosphere about the mouth of the horn.

2. In an article of the class described, the combination of a base adapted to receive a reproducing unit, a horn for such unit carried by said base, an anchor in the form of a tripod, the legs thereof being inside of the horn and secured to the base, the head of the anchor being held axially of said horn, a lighting and shade-supporting fixture including a stem, said stem being secured to the head of said anchor, and a shade carried by said fixture and cupping the atmosphere about the open end of said horn.

3. In an article of the class described, the combination of a base adapted to receive a reproducing unit, a horn for such unit carried by said base, an anchor secured to the base within the horn, a lighting and shade-supporting fixture reaching through the horn without contact therewith and secured

to said anchor, and a shade carried by said fixture and cupping the atmosphere about the open end of said horn.

4. In an article of the class described, the combination of a base adapted to receive a reproducing unit, a horn for such unit carried by said base, a lighting and shade-supporting fixture also carried by the base, a shade cupping the atmosphere about the mouth of said horn, said shade having a central opening therein and mounted on said support with said opening aligned axially with the mouth of the horn and an adjustable shutter device for said opening adapted to variably obstruct the passage of sound from the horn through said opening in said shade.

5. In an article of the class described, the combination of a base adapted to receive a reproducing unit, a horn for such unit carried by said base, a lighting and shade supporting fixture also carried by the base, a shade cupping the atmosphere about the mouth of the horn and formed to permit of the unobstructed passage of sound from the horn centrally therethrough, and an adjustable shutter arranged to control such exit of sound from said part of said shade.

6. In an article of the class described, the combination of a base adapted to receive a reproducing unit, a horn for such unit carried by said base, a lighting and shade-supporting fixture reaching through said horn and anchored to said base, and a shade carried by said fixture and encompassing the atmosphere about the open end of said horn.

7. In an article of the class described, the combination of a base adapted to receive a sound reproducing unit, a horn for such unit, an anchor associated with said base, 40 said anchor including reaches traversing the restricted receiving end of said horn and also including a head into which said reaches merge, a fixture stem carried axially of the horn and mounted at the restricted 45 end thereof in the head of said anchor, a lamp supported upon the stem, and a shade for said lamp supported upon said stem to receive and conceal the bell of said horn.

8. In an article of the class described, a 50 base adapted to receive a sound reproducing unit, a horn for such unit, an anchor on said base reaching into the receiving end of said horn, a fixture stem fitted in said anchor and reaching out of the mouth of 55 said horn, and a lamp and a shade therefor, both supported by said stem.

9. In an article of the class described, a base adapted to receive a sound reproducing unit, a horn for such unit, a fixture stem, 60 an anchor on the base fitting within the restricted end of said horn and registering the same with respect to the outlet of such unit, said anchor serving also to rigidly secure said horn and said stem to said base, said 65 stem being extended out of the mouth of the horn, and a lamp and a shade therefor, both supported by the stem.

In testimony whereof, I have signed my name to this specification.

FRED C. CASWELL.
